UNITED STATES PATENT OFFICE.

ISAAC A. ROMMER, OF BROOKLYN, NEW YORK, ASSIGNOR TO IDEAL NOVELTY AND TOY CO., OF BROOKLYN, NEW YORK, A CORPORATION OF NEW YORK.

DOLL'S EYES.

Application filed November 12, 1924. Serial No. 749,453.

To all whom it may concern:

Be it known that I, ISAAC A. ROMMER, a citizen of the United States of America, and a resident of the city of New York, borough of Brooklyn, in the county of Kings and State of New York, have invented new and Improved Dolls' Eyes, of which the following is a description.

My invention relates to dolls' eyes and 10 particularly relates to means for properly positioning the eyes at the openings in the doll's head.

In practice in the mounting of the dolls' eyes by the ordinary methods if the eyes 15 be maintained in close relation to the wall defining the openings in the head, at the eyes, the eye-balls rub and sometimes bind. On the other hand, if the eye be so placed 20 to leave perfect freedom of movement to prevent its binding against the edge of the openings, there is an apparent gap or space which makes the eyes unattractive.

The general object of my invention is to 25 overcome the defects referred to and the stated object is accomplished by yieldingly 30 mounting the eyes to be subject to spring pressure so that the eyes are maintained in the proper close relation to the edges of the openings while at the same time binding of 35 the eyes at the openings is prevented.

A further important object of the invention is to provide pendulous weights for the 35 eyes and so connected thereto as to permit the weights to swing laterally, thereby avoiding the possibility of the weights bending 40 parts appurtenant to the eyes.

Reference is to be had to the accompanying 45 drawings forming a part of this specification, it being understood that the drawings are merely illustrative of one example of the invention.

Figure 1 is a vertical section of the front portion of a doll's head illustrating my improved doll's eyes emplaced therein and 45 shown in side elevation;

Figure 2 is an enlarged rear elevation of the eyes and a fragment of the head;

Figure 3 is a horizontal section on the line 3—3, Figure 2;

50 Figure 4 is a fragmentary view with an eye shown in side elevation as in Figure 1 but on an enlarged scale.

In carrying out my invention in accordance with the illustrated example, the con-

cavo-convex element 10 representing the eye 55 as usual is formed at the back edge with rearwardly extending ears 11 having slots 12 therein, through which slots pass laterally directed ends 13 on a bowed yoke 15 pertaining to each eye, said ends 13 being received in recesses 14 in the head A in the opposite side walls of the usual opening A in the doll's head.

Spring means is provided as hereinafter described yieldingly maintaining the eye 65 ball against the walls or edges of the sockets or openings a in the doll's head and to overcome the friction caused by the spring pressure, I employ substantial weight on the pendulous arm (16). In order that the increased weight may not bend parts appurtenant to the eyes 10, I swingingly connect said arms 16 with the ears 11 by the medium of knuckles 116 through which the bent 70 ends 216 of said arms pass. The connection 75 permits the pendulous arms 16 to sway laterally relatively to the ears 11 so that said ears are not bent by the sidewise movement of the arms.

In order to yieldingly maintain the eyes 80 10 in the openings or sockets a and pressed gently against the edges at the front of said openings, I provide spring means to exert pressure against the eyes in a forward direction. Advantageously, the spring means 85 is provided through the medium of vertical wires 17 returned on itself and passed through holes 18 in the upper and lower ears 19 on the eyes 10 to effect engagement 90 between said wires 17 and the eyes. The re-

turned ends of the wire 17 at the top and at the bottom thereon are deflected laterally and constitute spring arms 20, the ends 21 of which are slightly curved and passed through the slots 12 in front of the ends 13 of yokes 15. Thus, the free ends 21 of the spring arms 20 exert rearward pressure against the fixed ends 13 as abutments for which reason the opposite ends of the springs integral with the vertical wires 17 exert forward pressure against the eyes 10 at the ears 19. Thus, the eyes are pressed gently in place against the edge portions of the openings or sockets a. Hence, the eyes 10 may yield as they turn in the event of a tendency 100 to bind against the edge portions of a head at the openings a as the eyes rock under the action of the arms 16, whereby binding is 105

positively prevented and yet the eyes are maintained in close engagement with the edges of the eye openings or sockets.

I would state in conclusion that while the 5 illustrated example constitutes a practical embodiment of my invention, I do not limit myself strictly to the exact details herein illustrated, since, manifestly, the same can be considerably varied without departure 10 from the spirit of the invention as defined in the appended claims.

Having thus described my invention, I claim:

1. A doll's eye having slots at the sides, an 15 element having members extending through said slots rockably mounting the eye, and spring means attached to said eye and bearing against said members, said spring means tending to press the eye forwardly relatively 20 to said members.

2. A doll's eye having slots therein at the sides, members extending through said slots and rockably mounting the eye, means to rock the eye on said members, and spring 25

arms having connection with the eye and 25 bearing against said members tending to press the eye forwardly relatively to said members.

3. An eye having slots therein at the sides, members extending through said slots and 30 rockably mounting said eye, means to rock the eye on said members, and spring means comprising resilient arms bearing against the said members and members on the eye at the top and bottom to which said spring 35 arms are secured.

4. An eye having slots therein at the sides, members extending through said slots and rockably mounting said eye, means to rock the eye on said members, and spring means 40 comprising resilient arms bearing against the said members and members on the eye at the top and bottom to which said spring arms are secured; together with an element integral with and connecting said arms and 45 engaging the eye at the top and bottom.

ISAAC A. ROMMER.
